UNITED STATES PATENT OFFICE.

CLARK ROBINSON, OF HARTLEY, IOWA, ASSIGNOR OF ONE-FOURTH TO
MOSES J. YOUNG, OF SAME PLACE.

INSIDE BLIND.

SPECIFICATION forming part of Letters Patent No. 396,115, dated January 15, 1889.

Application filed August 13, 1888. Serial No. 282,617. (No model.)

To all whom it may concern:

Be it known that I, CLARK ROBINSON, of Hartley, in the county of O'Brien and State of Iowa, have invented certain new and useful Improvements in Inside Blinds, of which the following is a specification.

My invention relates to the construction of inside blinds; and it consists in the combination, with a sheet of flexible textile or other suitable material, of slats applied to both faces of the sheet, the slats on one face being directly opposite those on the other face.

The drawing is a sectional perspective view illustrating my invention.

15 In the construction of inside blinds according to this invention I take a sheet, A, of some suitable flexible material that is strong and will not readily tear—such as paper and textile goods—and preferably of a width corresponding to the width of the blinds to be made, and apply to both faces thereof the slats B. The manner of securing the slats in position upon the sheet is a matter that may be varied considerably; but I prefer to use a 25 cement or adhesive substance, which does not disfigure the slats, as would tacks or similar fastenings. The slats are applied to the faces of the sheet, and preferably pressed in any suitable manner, so as to insure their adhesion to the flexible material throughout 30 their entire length. The slats on each face are arranged parallel to but separated from one another, so as to permit the blind to fold up compactly without stretching or tearing 35 the flexible sheet. If desired, the sheet A may be impregnated with a fire-proof compo-

sition, or made of a fire-proof material, such as asbestos.

The blind herein described and shown is cheap and simple in construction, and folds 40 readily, and is found to wear well.

I am aware that the slats of inside blinds have been strung upon narrow strips at either end of the slats, and to such a construction I make no claim.

45 It will be noticed that the portion of the flexible sheet A between the rows of slats permits a subdued light to enter, and by making this sheet of colored material a pleasing effect is secured.

50 The slats will advisably, though not necessarily, be made of wood.

Having thus described my invention, what I claim is—

1. As an improved article of manufacture, 55 the material herein described, comprising a flexible sheet and slats applied to opposite faces thereof, said slats being separated from one another a sufficient distance to permit their folding one upon the other.

60 2. In combination with the flexible sheet, the slats applied to both faces thereof directly opposite each other, those on the same face of the flexible sheet being separated from each other, substantially as shown, whereby 65 the fabric may be folded upon itself.

In witness whereof I hereunto set my hand in the presence of two witnesses.

CLARK ROBINSON.
